BOX AND SIMILAR CONTAINER

William J. Cella, Forest Hills, N. Y.

Application September 16, 1948, Serial No. 49,510

1 Claim. (Cl. 217—14)

1

This invention relates to boxes and similar containers, and particularly boxes of substantial and sturdy construction in which the walls and bottom are composed of wood or similar stiff and strong material, and the boxes are intended for holding relatively heavy goods, such as milk bottles or other bottled goods.

One of the objects of the invention is to provide a box of this character which shall be foldable or collapsible, permitting the box to be collapsed or flattened for shipment and storage, thereby enabling a relatively large number of these boxes to be packed or stored in space normally required for one or two of boxes of the non-collapsible type.

The invention further contemplates the provision of a collapsible box of this character which, while foldable or collapsible, is nevertheless extremely rigid and strong when erected and is capable of withstanding a great deal of rough handling and abuse without the possibility of collapse while in use.

Still another object of the invention is to provide a collapsible box which can be instantly erected or collapsed without requiring the use of tools; which when in its collapsed or flattened condition will be in the form of a relatively flat panel occupying very little space, and when erected will be rigid and sturdy and easily capable of bearing its contained load without becoming distorted or wobbly or losing its desired rectilinear shape.

These and other objects are attained by the invention, a more particular description of which will hereinafter appear and be set forth in the claim appended hereto.

In the accompanying drawing, wherein an illustrative embodiment of the invention is disclosed, Fig. 1 is a top plan view of a box or container constructed according to the invention; Fig. 2 is a side elevation of the same; Fig. 3 is an end view of the same; Fig. 4 is a perspective view of one of the corner hinges; Fig. 5 is a bottom view of the box; Fig. 6 is a top plan view of the box in its folded or collapsed condition; Fig. 7 is a perspective view of the second type of corner hinge employed in the box, and Fig. 8 is a transverse sectional view through the lower portion of the box body near one end thereof.

The box shown in the drawing is composed of five main elements, namely the side walls 1 and 2; the end walls 3 and 4, and the bottom 5, these parts being hingedly joined together in a manner to be set forth, whereby the box, when in its erected condition as seen in Figs. 1 to 3 and 5, will form a sturdy, rigid structure, and when in its folded or collapsed condition as seen in Fig. 6, will be compact and occupy relatively little space, thus rendering it convenient for packing, storing and shipping.

10 The side walls, end walls and bottom of the box are preferably, but not necessarily, composed of wood, or the same may be composed partly of wood and partly of corrugated board or other sheet material, the strength and thickness of the material employed being largely dependent upon the nature of the goods to be contained in the box. In the form shown, each of the walls of the box, as well as the bottom thereof, may be composed of a frame, consisting of strips 6, and a panel, consisting of the sheet shown at 7, these elements being nailed or otherwise suitably fastened together in any known manner to provide a side wall or bottom for the container.

15 At one end, or that shown at the upper right in Fig. 1, the side wall 1 is hingedly coupled to one end of the end wall 3 by a hinge or pivotal connection consisting of the two channel members 8 and 9 connected pivotally by the rivet or pin 10. The channel member 8 embraces the top edge of the side wall 1 and is secured to said wall by means of the rivets 11 or equivalent fastening elements. Similarly, the channel member 9 embraces the top edge of the end wall 3 and is fastened to said end wall 3 by means of the rivets 12 or equivalent fastening elements. Channel member 8 is formed with a lug 13 which overlies the top of the member 9 and is pivotally attached to the same by the pivot pin 10. This hinge construction, shown at the upper right in Fig. 1 at the top of the box is duplicated at the same corner of the box at the bottom. This hinge is also duplicated at the top and bottom of the diagonally opposite corner of the box, as indicated at 14, said hinge construction 14 serving to pivotally attach one end of the side wall 2 to one end of the end wall 4 in the manner explained in connection with the side wall 1 and end wall 3. The hinge above described is shown in detail in Fig. 4.

20 The opposite end of the side wall 1, or that end which is remote from the hinge just described, is coupled to the second end of the end wall 4 by a slightly different form of hinge, shown in detail in Fig. 7. This last-mentioned type of hinge consists of an angular channel member 15 which fits over or straddles the top edge of the side wall 1 and is fastened thereto by means of the rivets 10 or equivalent fastening members. Said hinge member has an integrally formed channel portion 17 extending at right angles to the part 15, and the portion 17 fits over the top of a strip member 40 and is attached thereto by means of the rivet 18. Said strip member 40 constitutes a fixed right-angled extension of the side wall 1 and it thus forms a part of the end wall 4 when the box is in its erected position, as best seen in Fig. 7. The channel portion 17 is formed 25 with a lug 19 through which the pivot pin 20

extends to thus couple this hinge member 15 to a channel member 21 secured over the top of the end wall 4 by the rivets 22. This hinge construction just described, and shown at the upper left in Fig. 1 and also in Fig. 7, is duplicated at the same corner at the bottom of the box and is also employed at the diagonally opposite corner of the box at the top and bottom and designated at 23.

The four hinges described, and two of which are of the construction shown in Fig. 4, and the second two of the construction shown in Fig. 7, are employed at the top and bottom of the sides and end walls of the box at the corners thereof, as clearly seen in Figs. 1 to 6 of the drawings.

The bottom of the box, designated at 5, is hinged to the side wall 2 by means of supporting brackets which extend downwardly from the corner hinge members and have lugs 26 receiving the pivot pins 27 which enter channel reinforcements 28 on the ends of the bottom 5. These channel reinforcements are attached to the bottom by means of the rivets 29, clearly seen in Fig. 3.

When the box is in its folded or collapsed condition, as shown in Fig. 6, the bottom 5 is folded upwardly upon its hinges and is disposed vertically between the walls of the collapsed box. When the box is in its erected or operative position, the bottom is swung downwardly to its horizontal position, and its free end is then supported upon flanges 30 dependant from the lower hinge members on the side wall 1 of the box. It will thus be noted that the bottom 5 when in its lowered position is supported firmly by the brackets 25 and the flanges 30, and that the cover is actually disposed slightly below the lower edge 31 and 32 of the sides of the box as well as below the lower edges of the end walls of the box. This arrangement permits the bottom of the box to fit within the top of another box when one box is stacked on top of another. A flange 33 constitutes a stacking guide to facilitate the placement of one box on top of another.

From the foregoing, the operation of the described structure will be readily understood. In its erected condition, the box is shown in Figs. 1 to 3 inclusive, and Figs. 5 and 6. The bottom 5 being in its horizontal or lowered position, holds the walls of the box apart, and the box is thus maintained in a rigid and sturdy condition, particularly when filled with goods.

When the box is empty and it is desired to fold or collapse the same to the condition shown in Fig. 6, the bottom 5 is swung upwardly on its pivots 27, the beginning of such upward swing of the bottom being indicated in dotted lines in Fig. 8, until the bottom is in a vertical position. The walls of the box are then pivotally moved on the four corner pivots to cause them to assume the position shown in Fig. 6. It will be therein noted that the bottom 5 is now located vertically, or with its plane parallel to the plane of the walls, and is positioned between the walls of the box. It will be further noted that the strip portions 40, located fixedly at one end of the wall 1 and at the diagonally opposite end of the wall 2, retain their fixed angular position in respect to the side walls to which they are so attached. Since the pivot pins 26 are at the ends of these strips 40, the end walls 3 swing on these pivots 26 and can lie parallel to the side walls, but spaced therefrom sufficiently to permit the bottom 5 to be located between the

collapsed walls of the box. When the box is folded or collapsed, it will be noted that it is of rectilinear shape, with parallel sides and ends. It is therefore flat and compact and permits a large number of these boxes to be stacked in collapsed form on top of one another without toppling, and the packing, shipping and storing facilities of the collapsed boxes will be readily appreciated.

When the box is set up or erected, it is exceptionally sturdy and rigid and will perform the functions and readily stand the use and abuse to which similar non-collapsible boxes are subjected.

While I have described one embodiment of the invention, it is obvious that the same is not to be restricted thereto, but is broad enough to cover all structures coming within the scope of the annexed claim.

What I claim is:

20 An open top rectangular collapsible box comprising hingedly connected side and end walls and a bottom hinged at one side edge adjacent the lower edge of a side wall, two diametrically opposite ends of the side walls carrying a vertical strip extending normal to the plane of the side and forming a part of the adjacent end wall when the box is in set up condition and further acting as end walls for the box when collapsed, upper and lower hinge members at the corners 25 of the box, all of said hinge members being of U-shape and straddling upper and lower edges of the side and end walls, two of the diagonally opposite corners having said hinge members, each composed of two sections with one section 30 being of right angle formation in plan view and straddling the adjacent strip and adjacent end of the side wall and being pivoted to the other hinge section beyond the strip in the zone of the end wall, and the other two diagonally opposite 35 corners having said hinge members pivotally connected at the corners of the box, the bottom of the box being of lesser length and width than the box body and occupying a position below and inwardly of the side and end walls of the box 40 when the latter is in set up condition for the vertical nesting of boxes, the hinge mounting for the bottom comprising a pair of downwardly extending brackets secured to the inner face of each of the side walls and projecting below the 45 bottom plane of the box body with a terminal portion on each bracket extending inwardly parallel with the bottom plane of the box, the brackets at one side having ears upstanding from said terminal portions and between which a 50 side edge of the bottom is pivotally mounted with the pivots spaced inwardly of the inner face of the adjacent side wall and the brackets at the opposite side forming supports for the free edge of the bottom.

60 WILLIAM J. CELLA.
